THREAD FORMING APPARATUS

Clarence E. Hahn, Euclid, and Oscar A. Boyer,
East Cleveland, Ohio, assignors to General Electric Company, a corporation of New York

Application December 7, 1938, Serial No. 244,414

6 Claims. (Cl. 153—72)

Our invention relates to apparatus for forming threads in metal shells and more particularly to apparatus for rolling threads in metal shells such as those used for electric lamp bases or sockets or the like. It is an object of our invention to provide apparatus for threading metal shells of this nature more rapidly and economically than heretofore. Another object of our invention is to provide a machine for threading the metal shells more accurately and uniformly than heretofore. Still another object of our invention is to provide a machine of this type which is less subject to wear and breakage. Other objects and advantages of the machine of our invention will be apparent from the detailed description which follows and the accompanying drawings thereof.

In the drawings, Fig. 1 is a plan view of a shell threading machine comprising our invention; Fig. 2 is a side elevation of a portion of the machine showing the metal shells as they are being fed into the machine; Fig. 3 is a vertical section through the machine along the line 3—3 of Fig. 1; Fig. 4 is a vertical section through the turret and thread forming portions of the machine along the line 4—4 of Fig. 1; and Fig. 5 is a perspective view of means for unloading the threaded metal shells from the machine.

The threading machine comprising our invention, as shown in the drawings, roll threads in the sides of the cylindrical metal shells 10 which are introduced thereto, as shown in Figs. 1 and 2, through the channel formed by the bracket 11 (only partially shown) and the bar 12. The metal shells 10 in this instance are those used for lamp bases and are, in general, cylindrical with one end completely open and the opposite upper end rounded off or inwardly flanged with a somewhat smaller opening therein. Because of the smaller opening in one end of the shells and the necessity of positioning the threads thereon, they all must be similarly orientated in the channel. The shells 10 are pushed through the channel by the feeding means (not shown) which introduces them into said channel, and are kept from bunching up and climbing over each other by a bar 13 mounted directly thereabove. The open ends of the shells rest on the plate 14 until they advance onto the clockwise rotating disc 15 which then advances them further along the channel.

The disc 15 is one part of a feeding mechanism of the threading machine which brings the shells 10 separately into alignment with the spindles 16 of the constantly rotating turret 17 and then causes them to be placed over the end thereof. The said disc 15, as shown in Fig. 3, is mounted on the hub 18 which is fastened to the upper end of the shaft 19 which in turn is mounted on the ball bearings 20 and 21 held by a separated top portion 22 of the frame of the machine directly

over the center of the turret 17. The motion of the disc 15 carries the shells against the periphery of the ring or spider 23 and into the pockets 24 thereof which are only large enough to accommodate a single shell so that the shells are carried away one at a time as the ring is turned in a clockwise direction. The said ring 23 is attached to and turned by the turret 25 which is fastened to the shaft 26 which in turn is mounted in the ball bearings 27 and 28 carried by the frame portion 22. During the movement of the ring 23, the shells 10 are carried off the disc 15 and onto the lip 29 of the bracket 11, the main body portion of which blocks off the remaining shells in the channel and prevents more than the single shell contained wholly within the pocket 24 from being fed from said channel.

The rotative motion of the ring 23 advances the shells 10 along the lip 29 until they are brought into engagement with the finger 30 and are carried beyond the edge of said lip 29. At this time, the higher speed of rotation of the ring 23 brings the pockets 24, in which the shells are contained, in alignment with the spindles 16 of the turret 17, whereupon the plungers 31 are caused to move down and force the shells onto the upper ends of the spindles 16. The proper transfer of the shells from the pockets 24 to the spindles 16 depends to a large extent on the proper alignment of the shells therewith and therefore depends upon the finger 30 which is pivoted on the screw 32 extending from the bracket 11 and which presses said shells back into the deepest portion of the pocket 24. The finger 30 is kept against one of the shells 10 at all times by the expanding force of the spring 33 which is located between the end of said finger 30 and the screw 34 carried by bracket 11. The stop screw 35 limits the movement of the finger so that it does not strike the ring 23 when there are no shells in the pockets 24 adjacent thereto. The walls of the pockets 24 align the shells 10 properly with the spindles 16 and, together with the finger 30, support said shells by friction until the plungers 31 are moved down. The plungers 31 are held by the bushings 36 carried by the turret 25 and are normally held in the raised position by the cam 37 which extends under the heads 31' on the upper end of said plungers 31. The cam 37 is a stationary machine member and drops in height very sharply at the point the plunger 31 is to move down. The said cam 37 is supported by the shaft 26 and the turret 25, the latter of which is engaged through the ball bearing 38, and is held in a fixed position by the arm 39 (Fig. 1) which is attached thereto and to the frame portion 22 by means of the stud 40 and the thumb nut 40'. As the plunger 31 is about to be moved down, the heads 31' thereof pass under the leaf spring 41 which extends from the outer end of the arm 42 and is bent upward

thereby. As the plunger 31 moves down, the spring 41 straightens out to the position shown in Fig. 3. If a distorted or defective shell 10 which will not pass over the end of the spindle 16 is carried into position above said spindle 16, it is carried by the ring 23 to one side thereof and drops down out of the way.

During the continuing rotative movement of the turret 25, the head 31' of the plunger 31 again comes into contact with the cam 37 which is now inclined upward and raises the plunger 31 so that the lower end is lifted from the shell 10 on the spindle 16 and reaches its upper limit of movement before a shell is again fed into position below it. The necessary rotative motion is produced in the disc 15 and the turret 25 by the movement of the spindle carrying turret 17 which, as shown in Fig. 4, is provided with a gear 43 at its hub which meshes with the gear 44 shown in Fig. 3 intermediate the gears 45 and 46 on the shafts 19 and 26 respectively. The gear 44 is mounted on the shaft 47 which is supported by the ball bearings 48 and 49 carried by the frame portion 22. As shown in Fig. 4, the frame portion 22 is mounted on the top end of a hollow post 50 extending upward from the top surface of the frame 51 proper of the threading machine and extends out over the turret 17.

The movement of the turret 17 occurs at a uniform rate in a clockwise direction and advances the spindles 16, on which the shells 10 have been placed by the feeding mechanism of the machine, to a position under the shoe 52 and adjacent the semi-circular thread-forming die 53. This rotative motion of the turret 17 is caused by means not shown, preferably an electric motor and some form of speed reducer which engage the ring gear 54 carried by said turret 17 through the gear 55 on the shaft 56. The shaft 56 is held in bearings, one of which is shown at 57, carried by the top of the frame 51 which keeps it in position.

The segmental die 53 provides the means of rolling the threads into the shells 10 and is provided on its face adjacent the spindle 16 with threads which are pressed into the shell 10 thereon as it rolls around the arcuate threaded surface thereof. The threads in the die 53 have substantially the same form as those provided in the upper end 58 of the spindles 16 within the shells 10 and the same angularity although they must be left handed when the threads in the shell are right handed. The spindle 16, as shown, is carried by the ball bearings 59 and 60 and held by the turret 17 and is rotated by the engagement of the gear 61 on the lower end thereof with the ring gear 62 attached to the top of the frame 51. The pitch diameter of the gear 61 is equal to that of the threads on the upper end 58 of the spindle 16 and causes the shell 10 to roll on the die 53 and to be bent to the shape of said threads. The collar 64 and the split cone 63 enable the spindle 16 to be rotatably adjusted relatively to gear 61 so that the threads on the upper end 58 and those on the die 53 can be matched at the assembly of the machine.

Although the threads in both the die 53 and spindle 16 are of full depth, the formation of the threads in the shell 10 takes place very gradually as the die 53 is slightly more curved than the path of movement of the inside edge of the shell 10 and engages the shell 10 fully only at its midpoint. The die 53 is fastened to the frame portion 22 and is capable of being adjusted both in and out and vertically; in the former manner by the adjusting screws 65 along the inside face and

the ends, and in the latter manner by the threaded bushings 66 located at intervals therealong. The bushings 66 rest against the frame portion 22 and hold the die 53 in the desired position when the bolts 67 extending therethrough are tightened down.

Because the relative position of the die 53 and the spindles 16 must remain constant, additional support is provided for the side of the frame portion 22 adjacent the die 53 by the pair of brackets 68 which are bolted to the frame 51 and to said frame portion 22 through the bolts 69. Holes in the die 53 allow the bolts 69 to extend therethrough. Additional support is also provided for the turret 17 at the rim by a plurality of ball bearings 70 (only one of which shows in Fig. 4) which are mounted on a stud 71 carried by block 72 mounted on the frame 51 of the machine.

The rotative motion of the turret 17 is also used to actuate an oil pump 73 which forces the lubricating oil to the various parts of the machine. The pump 73 comprises the piston 74 which is located in a well in the frame 51 and which engages the cam surface 75 on the bottom of the turret 17. The rotation of the turret 17 carries raised portions of said cam surface 75 against the head of the piston 74 which is thereby forced down in the well in the frame 51 and in the opening in the cap 76 over the lower end thereof, so that the oil contained within the opening in the cap 76 is forced out the pipe 77. The return upward motion of the piston 74, which causes the oil to be sucked up into the opening in the cap 76 from the pipe 78, is caused by the expansion of the spring 79. The check valves 80 and 81 in the pipe lines 77 and 78 prevent the oil from flowing in the opposite direction and destroying the pumping action of the piston 74.

Since there is a possibility of the shell 10 shifting on the spindle 16 so that the threads will not be true to pitch or correctly positioned thereon, said shells 10 are held down by the shoe 52 which extends over said shells for substantially their full path of travel adjacent the die 53. The shoe 52 is supported by a plurality of studs 82 which extend up through the end of the brackets 83 mounted on the frame portion 22 and is separated from said brackets 83 by the coiled springs 84.

Following the gradual withdrawal of the threads on the die 53 from those formed in the shells 10, said shells are advanced into an unloading position at which they are engaged by the rapidly moving periphery of the leather wheel 85. The wheel 85 as shown in Figs. 1 and 5 is attached to the drive shaft 86 of an electric motor 87 and is turned in a direction causing the shells 10 to be rotated and unscrewed from the threads on the upper portion 58 of the spindle 16. The speed with which the shells 10 leave the spindles 16 is sufficient to carry them upward into the tube 88 where a blast of air from the nozzle 89 blows them sideward into the main portion thereof which carries them to a receptacle (not shown) below the opening in the lower end thereof. In order to permit the position of the wheel 85 to be adjusted, the motor 87 is mounted on a slide 90 in ways in the bracket 91 which is mounted on the frame 51. Adjustment of the position of the slide 90 is accomplished by rotating the thumb wheel on the end of the screw 92 which is held by a portion of the bracket 91 and screws in and out of said slide 90. A series of

arcuate plates 93 which rest on the raised ridge 94 on the frame 51 is provided about the turret 16 to guard the lower part thereof and keep objects from entering the mechanism of the machine therebelow.

What we claim as new and desire to secure by Letters Patent of the United States is:

1. Apparatus for rolling threads in a metal shell comprising a threaded spindle arranged to receive the metal shell, a turret for supporting said spindle and moving it along a definite curved path, a segmental die member having a threaded face located adjacent said path, said die face being located at the inside of said path and being of greater curvature throughout its length than the adjacent portion of said path so that its ends are spaced slightly farther therefrom than its mid-section so that during movement of said spindle therealong the said die face is engaged by the side walls of said shell with varying pressure, and means for rotating said spindle during said movement to cause the shell to engage and roll the face of said die so that the side walls of the shell are gradually pressed into the threads of the spindle.

2. Apparatus for rolling threads in a metal shell comprising a threaded spindle arranged to receive the metal shell, a turret for supporting said spindle and moving it along a definite path, a die member having a threaded face located adjacent said path and arranged to be engaged by the side of the shell during its movement therealong, means for rotating said spindle during said movement to cause the shell to engage and roll along the face of said die so that the side walls of the shell are pressed into the threads of the spindle, and means for rotating the shell separately from said spindle in a direction causing said shell to be unscrewed and separated therefrom.

3. Apparatus for rolling threads in a metal shell comprising a plurality of spindles each arranged to support one of said metal shells, a circular turret for supporting said spindles at regular spaced intervals adjacent its periphery, a circular rotatable member having pockets therein adapted to hold single shells, said rotatable member being of smaller diameter than said turret and being mounted eccentrically thereto so that the circular line of movement of its pockets intersects the path of movement of said spindles at a given point, means for rotating the said turret and operating said circular rotatable member in proper time relation thereto to bring the said pockets over a spindle at said point of intersection, means for transferring the shells from said pockets to spindles at said point of intersection, a die member having a threaded face located adjacent the path of movement of said spindles in position to be engaged by the sides of the shells during the rotation of said turret, and means for rotating said spindles while they are adjacent said die member to cause the shells to engage and roll along the face of said die so that the side walls of the shells are pressed into the threads of the spindle.

4. Apparatus for rolling threads in a metal shell comprising a plurality of spindles each arranged to support one of said metal shells, a circular turret for supporting said spindles at regular spaced intervals adjacent its periphery, a circular rotatable member having pockets in its periphery adapted to hold single shells, said rotat-

able member being of smaller diameter than said turret and being mounted eccentrically thereto so that the circular line of movement of its pockets intersects the path of movement of the spindles, 5 means for rotating said turret and said circular rotatable member in proper time relation to each other to bring the said pockets over said spindles at a given point, plungers mounted above said pockets, means for causing a plunger at said 10 point of intersection to move into its corresponding pocket to push the shell therein onto a spindle when they are aligned, a die member having a threaded face located adjacent the path of movement of said spindles and in position to be engaged by the sides of the shells during the rotation of the said turret, and means for rotating said spindles while they are adjacent said die member to cause the shells to engage and roll along the face of said die so that the side walls of the shells are pressed into the threads of said spindles.

5. Apparatus for rolling threads in a metal shell comprising a plurality of spindles each arranged to support one of said metal shells, a turret for supporting said spindles at regular spaced intervals adjacent its periphery, feeder means having pockets therein adapted to hold single shells and movable in a direction intersecting the path of movement of said spindles, a channel arranged to conduct the shells to said feeder means, a rotatable disc located below said channel and the adjacent part of said feeder means arranged to support and advance the shells into the pockets of said feeder means as rapidly as they are presented to the end of the channel, means for rotating said turret and operating said feeder means in proper time relation thereto to bring the said pockets over said spindles at said intersection, means for transferring the shells from said pockets to said spindles when they are aligned, a die member having a threaded face located adjacent the path of movement of said spindles and in position to be engaged by the sides of the shells during the rotation of the said turret, and means for rotating said spindles while they are adjacent the said die member to cause the shells to engage and roll along the face of said die so that the side walls of the shells are pressed into the threads of said spindles.

6. Apparatus for rolling threads in a metal shell comprising a threaded spindle over which the metal shell is placed, a stationary center post, a horizontal turret rotatable on said post for supporting said spindle and moving it along a definite path, supporting frame means for said turret secured to said post and engaging the center portion and the rim of said turret, a horizontal die member having a threaded face located above said turret and adjacent the path of movement of said spindle and arranged to be engaged by the side of the shell during said movement of the spindle, means for supporting said die extending outward from said post over said turret, and additional die-supporting means extending over the path of movement of said spindle from the periphery of said first-mentioned supporting frame means, and means for rotating said spindle during said movement to cause the shell to engage and roll along the face of said die so that the side walls of the shell are pressed into the threads of said spindle.
